UNITED STATES PATENT OFFICE.

GEORGE WASHINGTON PARKINSON AND RALPH SOLOMON TOMPKINS, OF BEACON CITY, NEW YORK.

CUTTING ATTACHMENT FOR SEWING-MACHINES.

1,103,825.

Specification of Letters Patent. Patented July 14, 1914.

Application filed August 9, 1913. Serial No. 783,937.

To all whom it may concern:

Be it known that we, GEORGE W. PARKINSON and RALPH S. TOMPKINS, both citizens of the United States, and residents of Beacon City, in the county of Dutchess and State of New York, have invented a new and Improved Cutting Attachment for Sewing-Machines, of which the following is a full, clear, and exact description.

The object of the invention is to provide a new and improved cutting attachment for sewing machines, more especially designed for accurately cutting the welt on the brim of a felt hat during the time the welt is stitched in place and while a stiffening wire may be inserted in the welt.

In order to accomplish the desired result, use is made of a cutter reciprocating with the needle bar of a sewing machine, the cutting edge of the cutter being spaced from the sewing needle and being arranged approximately parallel to the line of feeding the material.

A practical embodiment of the invention is represented in the accompanying drawings forming a part of this specification, in which similar characters of reference indicate corresponding parts in all the views.

Figure 1 is a sectional front elevation of the sewing machine provided with two needles and with the cutting attachment arranged for cutting off both the inner and outer edges of the welt; Fig. 2 is a side elevation of the same; Fig. 3 is a sectional plan view of the same; Fig. 4 is a sectional front elevation of a sewing machine provided with a single needle and with the cutting attachment arranged for cutting off the inner edge only of the welt; Fig. 5 is a plan view of a portion of a felt hat brim provided with a welt double-stitched and trimmed at both the outer and inner edges; Fig. 6 is a similar view of a portion of a felt hat brim provided with a single-stitched welt trimmed along the inner edge only; Fig. 7 is a sectional side elevation of the brim material prior to turning over the welt; Fig. 8 is a similar view of the same with the material doubled up to form the welt; Fig. 9 is a similar view of the same with the welt double-stitched and with the outer and inner edges trimmed; and Fig. 10 is a similar view showing the welt single-stitched with the inner edge only trimmed.

The sewing machine on which the im-

provement is shown applied in Figs. 1, 2 and 3 is provided with the usual reciprocating needle bar A on which is secured a carrier or clamp B by the use of a suitable set screw B' or other fastening device. On the carrier B are secured the spaced needles C, C' by the use of set screws C² and on the said carrier B are adjustably secured cutters D, D' by the use of set screws E. The cutters D, D' are arranged on the opposite sides of the two needles C, C'. The cutters D, D' are adapted to pass through slots F', F² arranged in a presser foot F of otherwise usual construction. A feed bar H is adapted to feed the brim material in a transverse direction and a needle plate G is provided having the usual openings for the passage of the needles C, C' and the feed bar H, and also having a slot G' in vertical alinement with the slot F² for the passage of the cutter D'. An adjustable gage I is arranged for guiding the material while forming the welt. The brim J is provided with a portion J' doubled over and fastened in place by two rows of stitches J², J³, while feeding the brim J transversely under the needles C, C' by the use of the feed bar H.

It will be noticed that the cutters D, D' have their cutting edges arranged approximately parallel to the line of movement of the feed bar H, and the said cutting edges are on different levels so that when the needle bar A is in lowermost position the cutting edge of the cutter D has passed through the portion J' while the cutting edge of the other cutter D' has passed through both thicknesses at the outer edge of the brim, as will be readily understood by reference to Figs. 1, 5 and 9. From the foregoing it will be seen that the doubled-up portion J' is fastened by two rows of stitches J², J³ in place and the doubled-up outer edge of the welt is accurately trimmed by the cutter D', while only the inner edge of the doubled-up portion J of the welt is trimmed without danger of cutting into the brim J itself.

When it is desired to provide the brim J⁶ with a welt J⁷ fastened in place by a single row of stitches J⁸ and trimming the inner edge J⁹ of the welt J⁷ then use is made of but one needle C and the cutter D, as shown in Fig. 4. In this case the needle C forms a single row of stitches J⁸ while feeding the material transversely by the feed bar H and at the same time the cutter D trims off

the inner edge J^9 of the welt J^7 so as to give a fine finish to this inner edge of the welt.

In the construction disclosed in Fig. 4, the ordinary needle plate G can be used as the cutter D does not pass with its cutting edge lower down than the top surface of the brim J^6 at the time the needle bar A reaches its lowermost position.

By reference to Fig. 2, it will be noticed that the cutting edge of the cutters D and D' is of considerable length and preferably somewhat in excess of the throw of the feed bar H to insure a continuous cutting of the welt material, as above explained.

Having thus described our invention, we claim as new and desire to secure by Letters Patent:

1. The combination of a sewing machine and a cutting attachment, the sewing machine having a reciprocating needle bar carrying spaced sewing needles and a feed bar for feeding the doubled-up brim of a felt hat in a transverse direction, the said cutting attachment having two cutters reciprocating with the said needle bar, the cutters having cutting edges arranged in different horizontal planes.

2. The combination of a sewing machine and a cutting attachment, the sewing machine having a reciprocating needle bar carrying spaced sewing needles, and a feed bar for feeding the doubled-up brim of a felt hat in a transverse direction, the said cutting attachment having two cutters reciprocating with the said needle bar and arranged on opposite sides of the said needles, the cutters having cutting edges extending approximately parallel to the line of movement of the said feed bar, the said cutting edges being arranged in different horizontal planes, and the cutting edge of one of the cutters cutting through the thickness of the upper doubled-up portion of the brim at the time the needle bar is in its lowermost position.

3. The combination of a sewing machine and a cutting attachment, the sewing machine having a reciprocating needle bar carrying spaced needles, and a feed bar for feeding the doubled-up brim of a felt hat in a transverse direction, the said cutting attachment having two cutters reciprocating with the said needle bar and arranged on opposite sides of the said needles, the cutters having cutting edges extending approximately parallel to the line of movement of the said feed bar, the said cutting edges being arranged in different horizontal planes and the cutting edge of one of the cutters cutting through the thickness of the upper doubled-up portion of the brim at the time

the needle bar is in its lowermost position, and the cutting edge of the other cutter cutting through the doubled-up brim at the outer edge thereof and at a time the needle bar is in lowermost position.

4. In a sewing machine, the combination of a reciprocating needle bar, a reciprocating cutter carried by the needle bar and arranged to one side of the sewing needle and spaced therefrom, a presser foot having a slot for the passage of the said cutter, a needle plate, and a feed bar for feeding the doubled up brim of a felt hat, transversely of the needle plate, the length of the cutting edge of said cutter being in excess of the throw of the feed bar, the said cutting edge being spaced from the needle plate a distance equal to the thickness of the brim, at the time the needle bar reaches its lowermost position.

5. A cutting attachment for sewing machines, comprising a carrier attached to the needle bar of the sewing machine, and spaced cutters adjustably secured to the said carrier and having their cutting edges in different horizontal planes.

6. In a sewing machine, the combination of a reciprocating needle bar, a cutter attached to the needle bar to one side of the sewing needle, a presser foot having a slot for the passage of the said cutter, a needle plate, and a feed bar for feeding the material, the cutting edge of said cutter extending approximately parallel to the line of feeding, said parts being so arranged relative to each other that the cutting edge of said cutter is spaced from the needle plate when the needle bar reaches its lowermost position.

7. In a sewing machine, the combination of a reciprocating needle bar provided with a pair of spaced needles, a feed bar, a presser foot having two slots, a needle plate having a slot in register with one of the said presser foot slots, a carrier attached to the said needle bar, and cutters secured to the said carrier and having their cutting edges at different levels, the said cutters being adapted to pass through the said presser foot slots and the said cutter having its cutting edge lowermost being adapted to pass through the said needle plate slot.

In testimony whereof we have signed our names to this specification in the presence of two subscribing witnesses.
